UNITED STATES PATENT OFFICE.

FRANK P. HALL, OF SALIDA, AND WILLIE E. CALKINS, OF GUNNISON, COLORADO,
ASSIGNORS OF ONE-FOURTH TO SARAH A. HALL, OF SALIDA, COLORADO, AND ONE-
FOURTH TO GEORGIA A. CALKINS, OF GUNNISON, COLORADO.

SCRAPER AND GRADER.

Application filed January 14, 1922. Serial No. 529,361.

To all whom it may concern:

Be it known that we, FRANK P. HALL and WILLIE E. CALKINS, citizens of the United States, residing at Salida and Gunnison, respectively, in the counties of Chaffee and Gunnison, respectively, and State of Colorado, have invented certain new and useful Improvements in Scrapers and Graders, of which the following is a specification, reference being had to the accompanying drawings.

This invention relates to grading machines or scrapers such as are used on roads for the purpose of leveling the road or in leveling farm lands, this particular type of grader or leveler being designed for the purpose of cutting down small hills and filling small hollows in the road or surface so as to make the road or surface smooth.

The general object of this invention is to provide a machine for this purpose which is particularly effective in action and in which the blade carrying frame may be raised or lowered relative to the ground to any height desired.

A further object is to provide a leveler or grader of this character having a series of parallel blades, the blades being mounted for swinging movement, and means being provided whereby the blades may be angularly adjusted with reference to the line of draft.

A still further object is to provide means whereby the draft may be applied evenly and uniformly to the frame, blades and to the runners when the latter are in use.

Still another object is to provide a roller mounted at the rear end of the runners or supporting frame, which may be shifted into or out of operative position so as to be used in rolling the ground or road after the scrapers have passed over it, or which may be used when the runners are lowered to give a rolling support to the rear end of the frame, means being provided whereby a supporting wheel may be disposed at the forward end of the frame for supporting it, thus permitting the device to be readily transported from place to place.

Another object is to provide means whereby the line of draft may be caused to assume an angular relation to the axial line of the machine.

Other objects have to do with the details

of construction and arrangement of parts as will appear more fully hereinafter.

Our invention is illustrated in the accompanying drawings, wherein:

Figure 1 is a side elevation of a scraper and grader constructed in accordance with our invention;

Figure 2 is a longitudinal sectional view of the scraper and grader;

Figure 3 is a top plan view thereof;

Figure 4 is an under side plan view thereof;

Figure 5 is a fragmentary longitudinal section on the line 5—5 of Figure 1;

Figure 6 is a fragmentary vertical section on the line 6—6 of Figure 1;

Figure 7 is a fragmentary perspective view of one of the scraper blades, showing the member 32 attached thereto;

Figure 8 is a fragmentary vertical section through the beam 21 and slot 51;

Figure 9 is a fragmentary side elevation showing a modified form of the construction whereby the runners are raised or lowered;

Figure 10 is a fragmentary cross sectional view on the line 10—10 of Figure 9;

Referring to the drawings, it will be seen that we provide a scraper supporting frame and laterally disposed runners, these runners being so connected to the scraper supporting frame that the scraper supporting frame may be elevated or depressed relative to the runners so as to permit the machine to be readily transported, change the distance between the scraping blades and the ground, and otherwise adjust the blades.

More particularly, the runners, which are designated 10, extend longitudinally in spaced parallel relation to each other and are longer than the scraper supporting frame. Preferably, though not necessarily, these runners are made in two sections A and B, the section A being hinged to the section B by a hinge 11. Means are provided, as will be later described, for detachably engaging these two sections A and B in aligned relation or disengaging the sections so as to permit the section A to turn upon the hinge 11 and be raised relative thereto. The two rear sections A of the runners are connected by a transverse bolt 12, and disposed between the rear ends of the sections A is a roller 13. This roller is rotatably

- mounted at its ends in levers 14 which are pivoted to the rear section of the runners so that the roller may be raised or lowered to any extent desired.
- 5 The main frame consists of the medially disposed reach bar 15, the rearwardly diverging, longitudinally extending frame bars 16, and the transverse bars 17, 18, 19 and 20. These several frame bars are 10 rigidly connected to each other in any suitable manner. The ends of the transverse bars are engaged with longitudinally extending sills or beams 21. The forward end of the beam 15 is attached to the clevis 22 15 whereby draft may be applied to the machine, this clevis being attached by a king bolt 23 which extends down through the beam 15 and through a block 24 disposed below the beam, and disposed between this 20 block 24 and the beam 15 and the ends of the beams 16 is a draft evener 25 which is connected at its ends by chains 26 to the forward ends of the runners 10. Disposed between the longitudinally extending beams 25 21 and the outer ends of the beams 17, 18, 19 and 20 is a longitudinally extending strip of metal 27, and below this strip is the longitudinally extending strip 28 which, between the transverse beams 17, 18, 19 and 30 20, is cut away on an arcuate line, as at 29, these strips or plates 28 constituting guides. Disposed below the longitudinal beams 15 and 16 and between the transverse beams 17, 18, 19 and 20 are the scraper blades 30. 35 Each of these blades is pivotally mounted upon a bolt or spindle 31 extending upward through the beam 15, and the outer ends of these blades at their upper edges are provided with clips 32 which embrace the edge 40 of the guide 28, as illustrated most clearly in Figure 6. Thus it will be seen that all of these scraper blades 30 have parallel oscillating movement. The ends of each scraper blade are provided with the shackles 33 and 45 connecting these shackles are the longitudinally extending links 34. Pivotally mounted below the block 24 is an equalizer 35 to which the end links 34 are pivotally connected.
- 50 It is to be particularly noted that the blades differ in depth of cut, each blade being a little deeper than the blade in advance, that is the blades are deeper rearward so that the second blade will make a slightly 55 greater cut than the first blade and the third blade will make a slightly deeper cut than the second blade. The blades are shifted to or from a position at right angles to the line of draft or the longitudinal axis of 60 the blade supporting frame by means of cables 36 which pass over pulleys 37 mounted upon the rear beam 20, these cables then passing to drums 38 mounted upon shafts 39 supported in brackets 40 on the main 65 frame, these shafts being provided with hand wheels 41 whereby the shafts may be rotated to wind the cable up upon the drums. Means must be provided for holding each wheel in its adjusted position and we have illustrated for this purpose a locking lever 70 42 pivoted at 3 and adapted to be shifted so as to engage with the corresponding wheel to lock it from rotating movement, the rear end of the lever constituting means so disposed relative to the driver's seat 44 that 75 the lever may be readily kicked in or kicked out to lock one or the other wheels.
- It will be understood that when it is desired to shift the blades out of their right angular relation to the axis of the main frame, one of the wheels is turned to wind up the cable upon the drum, while the other wheel is turned to release the cable upon its drum. Then when the blades are adjusted, both of the wheels are locked in 85 place.
- It will be seen that with the construction illustrated, the strain upon the blades is transmitted to all of the blades and to the equalizer bar 35 and to the cables so that no 90 one blade is submitted to too great a strain. It will likewise be noted that the blades are disposed at a slight downward and forward angle. The cables are prevented from running off the pulleys 37 by any suitable 95 means, as for instance the cable retainers 45. Any other suitable means for preventing the cables from running off the pulleys may be used, however.
- Where the runners 10 are made in two 100 sections A and B, it is necessary to hold these sections in alignment under some circumstances, and to that end we provide the longitudinally extending spring leaves 46 which are rigidly mounted upon the forward section of the runner B and which extend over the rear section of the runner, each leaf having an inwardly extending pin 47 adapted to extend to a socket 48 and when extended into this socket locking the 105 two sections A and B together and preventing any breaking of the joint at this section.
- In order to provide for interlocking these sections and permitting the rear section to 110 be raised into angular position, we associate with each spring 46 the downwardly extending shaft 49 having a handle at its upper end, this shaft being formed with a slotted cam 50 disposed behind the spring 115 leaf so that when this handle is turned in one position the cam will shift the free end of the spring outward and carry the pin 47 out from the socket 48 and when the shaft is turned in the opposite direction the spring 120 leaf will spring inward and the pin will engage the socket.
- The only purpose of having the runners 125 formed in two sections is to permit the rear sections to be turned upward relative to the 130

forward runner sections so as to thereby reduce the total length of the machine and permit it to make relatively short turns and to be disposed more conveniently in a barn or shed. Ordinarily, however, the two sections of the runners will be in alignment with each other, and even in moving over roads having very short turns there will be no necessity of turning up the rear sections, as the roller 13 will permit the rear portion of the runners to slide relative to the forward portion and thus permit a short turn to be made. We do not wish to be limited, therefore, to the use of runners made in two sections and to the locking means which we have disclosed.

It is, of course, necessary that the blade carrying frame or main frame shall be adjustable in a vertical plane relative to the runners 10. To this end the forward and rear-ends of the beams 21 are formed with longitudinally extending slots 51, and disposed upon the exterior of these beams are the forward and rear bell crank or angular levers 52. The pivotal support for these levers is constituted by a transverse pin 53 carrying a roller 43 or anti-friction bearing operating within the corresponding slot 51 so that these levers not only have a rocking motion but a longitudinal motion also in the beams 21. The forward ends of these bell crank levers 52 are pivotally engaged with the runners and specifically, as illustrated, with the forward and rear ends of the forward sections B of the runners.

As illustrated in Figure 1, each rear bell crank lever 52 is connected to the corresponding arm of the first bell crank lever 52 by means of a connecting rod 55 so as to secure unitary motion of the two levers, and as illustrated in Figure 1, the rear lever 52 is upwardly extended and then laterally extended, as at 56, to form a handle disposed adjacent the seat 44 so that the driver may shift this lever. The rear lever 52 carries a tooth which is adapted to engage with a rack 57 over which it operates, the lever being sufficiently resilient so that it may be shifted laterally to carry its tooth out of engagement with the rack and to spring back with its tooth in engagement with the rack. Any other suitable means may be provided for this purpose. The construction which we have illustrated in Figure 1 is a particularly simple construction but it is not preferable for the reason that the driver must exert too much strength in order to raise and lower the frame relative to the runners, and preferably the construction illustrated in Figure 9 is used for this purpose.

In this case the forward and rear levers are connected by links 58 to a rack bar 59, and mounted upon a bracket 60 carried upon the corresponding runner 21 is a trans-

verse shaft 61 carrying a gear wheel 62 adapted to engage with the rack 59. The inner end of this shaft 61 is mounted in a bracket 63, in turn mounted upon the corresponding beam 21, the end of this shaft carrying a hand wheel 64. The shaft 61 is resiliently supported so as to permit the relative movement of the scraper supporting frame and the runners. The links 58 permit the rack bar 59 to always remain in contact with the gear wheel 62. A housing 59a is carried by the bracket 60 and engages over the rack bar 59 to hold it in place and guide it in its movements. Detents 61a, of course, are provided to prevent the shaft 61 from rotating rearwardly after it has been adjusted. Obviously any other gearing may be provided whereby the runners may be raised or lowered relative to the frame, or vice versa, and we do not wish to be limited to the construction illustrated. The hand wheels 64 will, of course, be disposed adjacent the driver's seat 44 so that he may readily adjust the runners at any time.

It will be obvious that by raising one runner relative to the frame and depressing the other runner relative to the frame that the blades will be disposed in a downwardly and laterally inclined position and that when both runners are disposed in the same relation to the frame the blades will extend horizontally. Thus the machine may be driven along one side of a road and may be caused to conform to the crowning of the road. The machine may be adjusted very readily to conform to irregularities in the contour of the ground.

Preferably the upwardly extending levers 14 which carry the roller 13 will both be connected by connecting rods 65 to foot levers 66 pivoted at 67, each lever carrying a dog 68 adapted to engage with a ratchet rack 69 to thereby hold the pedal or foot lever in adjusted position. Thus the roller may be depressed or raised as desired relative to the runners.

In order that draft may be applied at an angle to the axial line of the machine and the machine prevented from slewing around in line with the line of draft, we provide the links 70 which are pivoted at 71, the forward ends of the links being perforated for the passage of a pin 72, this pin being adapted to extend through any one of the holes 73 formed in the clevis 22. Thus it will be obvious that the tongue or clevis may be held at any desired angular relation to the line of draft.

In order to permit the machine to be readily transported over roads from place to place, a socket 74 is formed in the forward end of the reach bar 15, this socket being adapted to support the pintle of a caster wheel which may be inserted from beneath and will thus support the forward end of the

frame while the rear end of the frame may be supported by the roller 13. The caster wheel is shown in dotted lines in Figure 2.

The operation of the mechanism will be obvious from what has gone before, and it will be seen that by its use very effective leveling or grading operations may be carried on. This supporting frame may be raised or lowered relative to the runners to 10 thus raise or depress the blades, and it will be obvious that the old supporting frame may be mounted relative to the runners so that the blades are disposed in a downwardly and laterally inclined direction. The angle 15 of the blades may be changed very quickly and to suit the exigencies of service and the blades are held firmly in this inclined position while they are cutting and fully supported against strain. This machine requires only one man to operate it. The 20 blades cut the high places in the road or ground and carry the dirt it cuts off to the low places, thus filling them up. It digs no holes and is particularly valuable in evening 25 off the plow land. By using runners in place of wheels and making these runners relatively long, the machine will not dip into the hollows, thus cutting the hollows deeper, and will not cut too deeply in passing over 30 small hills, whereas were wheels used it would follow every inequality in the ground and would not, therefore, act to level the ground properly. The draft is all on the working parts and the blades are fully 35 supported against the strain to which they are subjected. All parts as far as possible are made of malleable cast iron. The blades, of course, will be of steel. The frame and the runners may be of wood but the runners, if made of wood, will be shod with runner 40 shoes.

While we have illustrated a construction which is particularly efficient for the purpose described, we do not wish to be limited 45 to this as it is obvious that many changes might be made in the details of this construction and arrangement of parts without departing from the spirit of the invention.

We claim:—

50 1. In a grading machine of the character described, a pair of parallel runners, a frame disposed between the runners and including elements extending parallel to the runners, blades mounted upon the frame, means whereby the frame may be vertically adjusted relative to the runners, said means 55 comprising a plurality of levers on each side of the machine, each lever being pivotally connected to one of the longitudinal members of the frame and to one of the runners, and manually operable means whereby the levers may be shifted to vertically adjust the 60 runners relative to the frame.

65 2. In a grading machine of the character described, oppositely disposed runners, a

frame disposed between the runners, blades mounted upon the frame, manually operable means whereby the frame may be vertically adjusted relative to the runners, said means connecting the runners to the frame, said 70 blades being mounted upon the frame for swinging adjustment relative to the line of draft, each of said blades being pivoted at its middle to the frame for movement into or out of right angular relation to the axis of the frame, links connecting the free ends of the blades to each other, and means mounted upon the frame whereby the blades may be swung upon their pivots in either direction. 75

3. In a grader of the character described, oppositely disposed, spaced runners, a frame disposed between the runners, manually operable means connecting the frame to the runners and permitting the frame to be vertically adjusted relative to the runners, said 80 means permitting the adjustment of one side of the frame independently of the other side of the frame, a series of transversely extending blades mounted beneath the frame, each blade being pivoted at its middle to the frame, links connecting the ends of the blades to each other, and manually operable means mounted upon the frame whereby the blades may be shifted into or 85 out of a position at right angles to the axis 90 of the frame.

4. In a grader of the character described, oppositely disposed, spaced runners, a frame disposed between the runners, manually operable means connecting the frame to the runners and permitting the frame to be vertically adjusted relative to the runners, said 100 means permitting the adjustment of one side of the frame independently of the other side of the frame, a series of transversely extending blades mounted beneath the frame, each blade being pivoted at its middle to the frame, links connecting the ends of the blades to each other, and manually operable means mounted upon the frame whereby the blades may be shifted into or out of a position at right angles to the axis 105 of the frame, the blade supporting frame being provided with arcuate guides at the ends of the blades, the ends of the blades slidingly engaging 110 said guides.

5. A grader of the character described comprising oppositely disposed, spaced runners, a frame disposed between the runners and having longitudinally extending slots, angular levers pivoted at one end of the runners and intermediate their ends having inwardly projecting bearings having reciprocating and oscillating movement in said slots, and manually operable means connected to the upper end of said angular levers whereby the angular levers may be shifted to thereby vertically adjust the supporting frame relative to the runners. 125

6. In a grader of the character described, 130

- a blade supporting frame, means for supporting the frame, a series of blades pivoted each at its middle to said frame for swinging movement into or out of a position at right angles to the length of the frame, links connecting the ends of said blades, guides supporting the ends of the blades, cables connected to the ends of the rearmost blade, pulleys on the frame over which said cables pass, independent winding drums mounted upon the frame and upon which said cables are wound, hand wheels for the winding drums, and means for locking the hand wheels in any desired position.
- 15 7. A grader of the character described comprising a blade supporting frame, laterally disposed runners on each side of the blade supporting frame, means connecting the frame to said runners and permitting vertical movement of the frame relative thereto, means for vertically adjusting the frame relative to the runners, blades mounted upon the under side of the frame for swinging movement into or out of a position at right angles to the line of draft, manually operable means for shifting said blades and holding them in their shifted positions, levers mounted upon the rear ends of the runners, manually controlled means for shifting said levers, and a roller carried by the lower ends of said levers and depressible thereby below the lower edges of the runners
- or shiftable to a position above the lower edges of the runners.
8. In a grader of the character described, 35 a pair of longitudinally extending runners, a scraper supporting frame mounted between the runners, scrapers carried thereby, means operatively connecting the frame to the runners and permitting vertical adjustment of the frame relative to the runners, said runners being formed in two sections, the rear sections being hinged to the forward sections for upward movement in a vertical plane into a rearwardly and upwardly extending 40 position, and means for detachably locking the rear sections in alignment with the front sections.
9. In a grader of the character described, 45 longitudinally extending runners, a scraper supporting frame mounted between the runners for vertical adjustments with relation thereto, a reach bar connected at the forward end of the frame and having a vertically extending socket adapted to receive the pintle 50 of a caster wheel to thus support the forward end of the frame upon said caster wheel, and ground engaging means at the rear end of the runners and depressible below the runners to support the same.
- 60 In testimony whereof we hereunto affix our signatures.

WILLIE E. CALKINS.
FRANK P. HALL.
